United States Patent Office

Des. 212,719
Patented Nov. 12, 1968

212,719

HIGH ASPECT RATIO AIRCRAFT

Andrew D. Galbraith, Sunnyvale, and Jack B. Baumann,
Los Altos, Calif., assignors to Lockheed Aircraft Cor-
poration, Burbank, Calif.

Filed Oct. 9, 1967, Ser. No. 8,911

Term of patent 14 years

(Cl. D71—1)

Fig. 1

Fig. 2

Fig. 3

FIG. 4

FIGURE 1 is a perspective view of a high aspect ratio aircraft showing our new design; and

FIGURE 2 is a side elevational view;

FIGURE 3 is a front elevational view; and

FIGURE 4 is a top elevational view thereof.

The characteristic features of our design as disclosed reside in the parts shown by means of full lines in the drawings:

We claim:

The ornamental design for a high aspect ratio aircraft, as shown and described.
